UNITED STATES PATENT OFFICE.

JAMES E. BANCROFT, OF TOLEDO, OHIO, ASSIGNOR TO THE NATIONAL RUBBER & SPECIALTIES COMPANY, OF CINCINNATI, OHIO, A CORPORATION OF OHIO.

VULCANIZER.

1,283,038.

Specification of Letters Patent. Patented Oct. 29, 1918.

Application filed March 5, 1914. Serial No. 822,599.

To all whom it may concern:

Be it known that I, JAMES E. BANCROFT, a citizen of the United States, residing at Toledo, Lucas county, Ohio, have invented a new and useful Vulcanizer, of which the following is a specification.

This invention relates to means for locally heating a substance.

This invention has utility when embodied in vulcanizers or means for treating certain materials as caoutchouc or rubber, being especially adapted for repair of objects made therefrom as pneumatic tires and the inner tubes and casings therefor.

15 Referring to the drawings:

Figure 1 is a medial vertical section through an embodiment of the invention in a portable vulcanizer;

20 Fig. 2 shows the vulcanizer of Fig. 1 in position for a casing repair, instead of mending an inner tube patch as shown in Fig. 1;

25 Fig. 3 is a plan view of the vulcanizer of Fig. 1, with portions broken away; and Fig. 4 is a side elevation of the vulcanizing member.

The vulcanizer embodies the bail or clamping member 1 having the threaded arms 2 with which coact the adjusting nuts 3, which are winged to permit ready manipulation. With the wings of the lower pair of nuts 3 disposed at right angles to the plane of the bail 1, they act as feet in carrying the vulcanizer elements 4, 5. The 30 elements 4, 5, are provided with a pair of laterally projecting ears each, each ear 6 having a slot 7 into which may be laterally moved the arms 2. The inner ends of these slots 7 have in the outer sides seats 8 with 35 which the nuts 3 may interfit. The lower vulcanizer element 4 may have a convex face or seat 9 for receiving the object to be vulcanized, as an inner tube 10, held in position thereon by the opposing vulcanizer elements.

40 The element 5 has the plugs 11 for closing the vents or fuel filling holes 12 leading to the annular chamber 13. This burner chamber 13 has nested therein the asbestos wick 14 bound with copper wire 15, the windings of which wire assist in giving the wick form as well as aid in vaporizing the hydrocarbon fuel conducted upward by the wick from the measured charge of alcohol or gasolene

supplied, owing to the upper portions of 55 the windings becoming heated and conducting such heat down into the chamber 13.

Centrally disposed as to the element 5 is the relatively independent vulcanizing member, shown as of circular form and mounted 60 as a plug in the annular burner. This vulcanizing member is provided with the vulcanizing face or seat 16 below the burner and opposing the seat 9 when the vulcanizer is used as in Fig. 1. In some instances the 65 element 4 need not be used as an opposing seat, for instance in the operation as disclosed in Fig. 2. About the face 16 are the threads 17 permitting interlocking engagement with the nut 18, insulated by the non-conducting packing 19 from the grooved underside of the burner element 5. Further heat insulating packing 20 is between the threaded portion 17 and the element 5. The nut 18 accordingly serves to maintain the 70 vulcanizing member in assembled relation as to the burner, and while the vulcanizing member is a heat conductor, the seat forming means or nut 18 is insulated from the source of heat, and in the clamped opera- 75 tive use of the vulcanizer, this nut 18 serves to temper heat action, localizing it to the vulcanizing member and holding the object firmly in position adjacent thereto as the lower face of the nut 18 and the vulcanizing member face 16 approximate a uniform 80 seat, in the instance shown being concave in one direction only.

With the vulcanizing member in position in the burner, the top outwardly extending 90 flange 21 of the vulcanizing member provides an annular opening between itself and the element 5 into which the draft for the burner comes to support combustion. The products of combustion from the annular 95 burner pass through the openings 22 in the cylindrical portion 23 of the member to thoroughly heat this central member. The vulcanizing member serves as a flue for the burner, the gases entering the openings 22 100 passing out through the hole 24 in the top. With the vulcanizing member formed of a good conducting material as metal, its temperature may be very nicely controlled solely by the flame action of the burner. In the 105 instance of the disclosure the conducting metal of the vulcanizing member is aluminum, making it readily responsive to all

changes. Owing to the flare 25 of the element 5 away from the vulcanizing member, there is with the packings 19, 20, complete metal insulation of the seat forming means 5 or nut 18 from the heat source and the burning action is the direct controller of the temperature of the face 16.

The burner is efficient in producing complete combustion of its entire charge in a 10 cleanly manner, even in tilted positions, say as shown in Fig. 2 wherein the action of the flue is as effective as in Fig. 1. The bail 1 not only serves as a handle for conveniently carrying the device, but may act as a clamp 15 in such various positionings of the vulcanizer for use as may be found desirable in practice.

The burner throughout is insulated from the vulcanizing member, and the heating of 20 the vulcanizing member is not from the burner receptacle, but from the products of combustion passing through the vulcanizing member as a flue for the burner. The intensity of the heating action upon the vulcanizing member is gaged by the design of 25 the structure to attain superior results in effective vulcanizing by a temperature uniform throughout the treatment. Any fluctuation in the temperature of the fuel receptacle in the burner element 5 is local thereto and may in no wise work deleteriously because the member accomplishing the treating is independent therefrom and has its 30 temperature controlled by combustion products which products insure uniform heating throughout the treatment of the vulcanizing member.

What is claimed and it is desired to secure by Letters Patent is:

- 40 1. The combination in a vulcanizer of a heat conducting member, a burner in which said member is mounted to be heated thereby, said member being provided with a heat imparting face below the burner.
- 45 2. The combination in a vulcanizer of a heat conducting member, an annular burner in which said member is mounted to be heated thereby, said member being provided with a heat imparting face.
- 50 3. The combination in a vulcanizer of a heat conducting member, a burner in which said member is mounted to be heated thereby, said member being provided with a heat

imparting face below the burner, and a wick 55 for said burner.

4. The combination in a vulcanizer of a burner, a wick for the burner, and heat conductor means spaced from the wick extending downward from the upper side of the 60 wick to assist in vaporization of the fuel for the burner conducted by the wick.

5. A vulcanizer providing with a vulcanizing member, an annular burner laterally thereof for acting on the member, and 65 means for detachably maintaining the burner and member in assembled relation.

6. A vulcanizer embodying a vulcanizing member, an annular burner exterior thereof, and means coacting to lock the burner and 70 member in detachably assembled relation.

7. A vulcanizer embodying a vulcanizing member, a burner surrounding the member, and means insulated from the burner and 75 engaging the member to hold the member and burner in assembled relation.

8. A vulcanizer embodying an annular burner, a vulcanizing member extending below the burner and forming a flue for the 80 burner, and a nut for locking the member in the burner.

9. A vulcanizer embodying a clamping U-bail in one piece, opposing vulcanizer elements each provided with seats for the arms of the bail, and on each arm an oppositely 85 acting pair of adjusting nuts coacting with the bail and elements for bringing the vulcanizer into operative position.

10. A vulcanizer embodying an integral U-bail having two threaded arms, oppositely 90 acting pairs of adjusting nuts on the arms, and vulcanizing face providing elements coacting with the arms of the bail and assembled on the bail by the nuts.

11. The combination in a vulcanizer of a 95 burner providing a central seat and a heat conducting member removably mounted in the burner seat to be surrounded by the burner and provided with a heat imparting vulcanizing face centrally below the burner. 100

In witness whereof I hereunto set my hand in the presence of two witnesses.

JAMES E. BANCROFT.
